UNITED STATES PATENT OFFICE

2,227,288

TAPPET CONSTRUCTION

Carl Voorhies and Harry E. Voorhies, Detroit,
Mich., assignors to Eaton Manufacturing Company,
Cleveland, Ohio, a corporation of Ohio

Original application August 3, 1936, Serial No.
94,040. Divided and this application July 21,
1939, Serial No. 285,766

4 Claims. (Cl. 123—90)

This invention relates to automatic compensating tappets for operating such parts as intake or exhaust valves of internal combustion engines, and more especially relates to improvements in the construction and arrangement of tappets of such character, and is a division of our application for Letters Patent of the United States for improvements in Tappet construction, filed August 3, 1936, Serial No. 94,040 now Patent No. 2,185,991, issued Jan. 2, 1940.

5 The principal object of the invention is to improve the automatic compensating mechanism of tappets especially adapted for operating movable parts of internal combustion engines.

10 Another object is to provide in a device of the above character a novel check valve construction and arrangement of such nature that the check valve means is closed by a force substantially equal to the force exerted by the engine valve operating gear when the engine valve is open.

15 A further object is to provide a novel plunger construction for hydraulic compensating tappets which includes means providing a seal between the plunger and its cylinder, and an inlet port 25 and a check valve means for the hydraulic compensating chamber of the tappet.

20 It is also an object of the invention to provide for a uniform rate of leakage from the hydraulic compression chamber of the tappet and to employ 30 a single element adapted to abut a plain surface for controlling such leak-down rates so that a single element may be accurately manufactured by a coining or stamping process.

25 Another object is to provide a system of construction which obviates the necessity of selective or other accurate fitting of plunger parts with respect to the cylinder therefor.

30 A still further object of the invention is to provide, in a tappet construction including a cylindrical body and a plunger arranged therein, for a mechanical hysteresis effect, i. e. a lagging or retardation of the movement of the plunger relative to its cylinder when forces acting axially upon the tappet ends are changed.

35 Another object is to provide, in a tappet construction, including a cylindrical body and a plunger arranged therein for defining in conjunction with said cylindrical body a hydraulic compression chamber, means for effecting a substantially complete seal between said plunger and cylindrical body, and means for permitting a definite and predetermined leakage or escape of liquid from said hydraulic compression chamber.

40 Other objects, features and advantages will

become apparent from the following description and appended drawings.

For the purpose of illustrating the genus of the invention, typical concrete embodiments are shown in the accompanying drawings in which:

Fig. 1 is a central vertical section of a tappet construction according to this invention;

Figs. 2 and 3 are transverse sections taken substantially on the lines 2—2 and 3—3 of Fig. 1;

Fig. 4 is a section showing a portion of an internal combustion engine and showing a tappet such as illustrated in Figs. 1 to 3 interposed between the valve operating cam and a spring seated intake or exhaust valve;

Fig. 5 is a fragmentary view similar to Fig. 1 of a portion of a modified form of tappet construction; and,

Figs. 6 and 7 are views similar to Fig. 1 of other modified forms of tappets constructed according to the principles of this invention.

Referring to the drawings wherein like numerals are applied to like parts in the several views, and referring more especially to Figs. 1, 2 and 3, there is shown a hydraulic compensating tappet construction comprising a cylindrical body 11, a plunger 12, a plunger spring 13, a coined or grooved valve 14 in the form of a washer, a plain or flat washer 15, and a yieldable but substantially incompressible washer or similar packing element 16 formed of a ductile metal. In the above washer-like elements 14, 15 and 16 are preferably, although not necessarily, maintained in position on the plunger 12 by means of a packing retainer washer 17 and a packing spring 18.

The tappet body 11 is provided with an annular recess 20 and one or more liquid admission ports 21 leading therefrom to the longitudinal bore 22 of the tappet body 11. Liquid may be admitted through the recess 20 and port or ports 21 into the longitudinal bore 22, from a suitable source of liquid supply, such as a lubricating system of an internal combustion engine. The lower end of the tappet body 11 is closed as indicated at 23 and is preferably provided with a hard wear-piece 24 adapted to engage the operating cam for an exhaust or intake valve of an internal combustion engine. The upper end of the cylindrical tappet body 11 is open for the reception of the plunger 12 and the latter is provided with a cylindrical portion 25 adapted to make a free sliding fit within the bore 22. The cylindrical portion 25 is provided primarily for guiding purposes. The spring 18 is arranged in a slightly compressed condition between the outer headed

end of the plunger 12 and the upper open end of the tappet body 11 for urging the plunger 12 outwardly with respect to the bottom of the bore 22. The plunger 12 is provided with an annular flange 26, the lower face of which, indicated at 5 27, is substantially normal to the axis of the plunger 12. The upper surface 28 of washer 15 is also a plain surface and the cooperating surfaces 27 of flange 26 and 28 of washer 14 are 10 both machined and polished so that when the washer is pressed upwardly by any material force leakage between the flange 26 and washer 14 is prevented.

The space 30 within the bore 22 of the tappet body 11, between the cylindrical portion 25 of plunger 12 and the valve member or washer 14 15 constitutes a preliminary or reserved liquid supply chamber for the tappet. The space within the bore 22 of tappet body 11 between the valve member or washer 14 and the bottom of the bore 22 constitutes the hydraulic compression chamber 20 25 of the tappet. Expansion of the spring 13 tends to cause the plunger 12 to move outwardly with reference to the tappet body until the end of 25 the plunger 12 contacts the end of the valve 33, as indicated in Fig. 4, and to cause end 23 of tappet body 11 to contact the valve operating cam, or the upper end of the plunger 12 and the lower end of the tappet body 11 contact other parts of valve operating mechanism. Outward movement of the plunger with reference to the tappet body creates 30 a partial vacuum condition within the compression chamber 31 and causes the upper surface 28 of the valve member or washer 14 to separate from the surface 27 of flange 26 and permits flow of liquid from the preliminary or reserved chamber 30 to the hydraulic compression chamber 31 until the latter chamber is filled with liquid and the pressure becomes substantially equalized between the chambers 30 and 31.

The lower face of the valve member or washer 14 is provided with a spiral groove 32 leading from its interior periphery to its outer periphery as indicated in Figs. 1 and 3. In actual practice this groove is of very small dimensions, and may be of other form than spiral where the desired resistance to flow can be obtained. The spiralling or otherwise lengthening of the groove 32 permits the same to be of sufficient length to afford the desired resistance to flow of liquid from the interior to the outer periphery of the valve member and still permit the groove 32 to be formed by mechanical processes with a desired accuracy so that a definite cross-sectional area and length of groove 55 32 may be had. This enables commercial production of grooved washers or valve members by coining or stamping processes so that definite leak-down rates can be obtained for large numbers of tappets with a result that uniform operation of all 60 of the tappets will be obtained. The washer 15 is preferably composed of metal and has its upper and lower surfaces plain and parallel, and these surfaces are machined and polished so that undesired or inadvertent leakage between the surfaces thereof and the surfaces with which they cooperate will not occur. The upper surface of the washer 15 cooperates with the grooved surface of the valve member or washer 14 so that the groove 32 provides a small cross-section passage preferably of extended length, the cross-sectional area and length of this passage 32 being uniform for all 65 tappets of the same type produced.

The washer is composed of a soft metal such as lead or soft alloys, such metal inherently having, 70 of course, a high degree of ductility. The inner

and outer peripheries of the washer or packing element 16 are preferably substantially of the same dimensions as the washer elements 14 and 15. The thickness of the washer 16, however, may be greater than that of either of the washers 14 or 5 15. If desired, a downwardly flanged packing washer 17 having substantially the same inner and outer peripheral dimensions as the preceding washer-like elements and a light packing spring 18 may be employed for retaining the ductile packing washer 16, washer 15 and valve member 14 10 in position. The spring 18 is very light so that any material difference in pressure between the preliminary chamber 30 and the hydraulic compression chamber 31 will allow admission of liquid 15 between the cooperating surfaces 27 and 28 of the flange 26 on plunger 12 and the valve member 14, provided the lesser pressure occurs in the hydraulic compression chamber 31.

During operation the tappet illustrated in Fig. 20 1, is interposed in a valve operating mechanism in the manner indicated in Fig. 4. Oil may be admitted through the annular recess 20 and ports 21 to the preliminary or reserve chamber 30, from the conventional lubricating system of the internal 25 combustion engine. Plunger spring 13 holds the upper end of plunger 12 against the valve stem, or an operating part therefor, and the closed end 23 of the tappet body against the cam shaft, or part operated thereby. When the plunger spring 30 13 causes outward movement of the plunger with reference to the tappet body a partial vacuum condition will be created within the hydraulic compression chamber 31 and the valve member 14 will not be held in tight engagement with the shoulder 35 26 on plunger 12. Oil then flows between the cooperating surfaces 27 and 28 of the flange 26 on plunger 12 and the valve member 14 from the preliminary chamber 30 to the hydraulic compression chamber 31. When the pressures are substantially 40 equal in the chambers 30 and 31, the washer or valve element 14 will be brought into contact with the surface 21 of flange 26 by the action of the light packing spring 18. As the cam shaft lifts the tappet body, the pressure of the oil in the hydraulic 45 compression chamber 31 is increased on two faces of the packing element 16, the inner peripheral surface and the lower surface of the packing element 16, and will tend to radially expand the packing element and force it outwardly against the wall of 50 the bore 22 of the tappet body and will also force it against the washer 15. The ductility of the material from which the packing element is constructed is such that the packing element 16 will actually be expanded into contact with the wall 55 of the bore 22 of tappet body 11 if not already in contact therewith, and will be maintained in firm contact therewith if already in contact with the wall, so as to effect a seal between the packing element and the tappet body, and the pressure of the sealing element against the washer 15 will effect a seal between these elements. This upward pressure is transmitted to the washer 15 forcing the latter into tight engagement with the valve member 14 so that no leakage can occur from the inner periphery of the valve member 14 to the outer periphery thereof except such leakage as is allowed by the spiral groove 32. This upward pressure likewise forces the smooth plain upper face 28 60 of the valve 14 against the corresponding face 27 on the flange 26 of plunger 12. Since the valve member 14 is pressed against the flange 26 by a force substantially equal to the entire load of the valve gear at the time of opening of the engine 65 70 75

valve, a seal between the valve member 14 and flange 26 is effected. When the engine valve is in closed position the pressure holding the valve member 14 against the shoulder 26 is released so that oil can seep between the surfaces of the washer elements 14, 15, 16 and 17 and between the valve member 14 and the shoulder 26 so that a cleaning cycle is provided. The spiral groove 32, due to its added length, may be used to provide for proper control of the leak-down rate of oil from the hydraulic compression chamber to the reserve supply chamber 30 without having the cross-sectional area of the groove too small for manufacturing purposes. During lift of the engine valve the grooved face of the valve member 14 is pressed against the flat smooth face of the washer 15 by a force substantially equal to the entire load of the valve operating mechanism. In this manner, the engine valve will be elevated without appreciable lift loss except that provided for by the groove 32 which controls the leak-down rate of oil flow between the hydraulic compression chamber 31 and the preliminary or reserve chamber 30.

As previously indicated the packing element or washer 16 is composed of yieldable or expandible metal of alloy of highly ductile character. The clearance between the inner periphery of the packing element 16 and the cylindrical portion of the plunger 12 surrounded thereby, is preferably quite small so that the packing element 16 is maintained in a substantially confined condition between the plunger 12, the washer 15, the wall of bore 22 of tappet body 11 and the packing washer 17 on the oil within the hydraulic compression chamber 31. With the packing washer 16 in a substantially confined condition, elevation of the tappet by operating cam shaft therefor will increase the pressure within the hydraulic compression chamber 31 and cause the packing element 16 frictionally to grip the wall of the bore 22 of tappet body 11 so as to cause a lagging or retardation in movement of the plunger 12 relative to the tappet body 11 when forces acting axially upon opposite ends of the tappet are changed. The packing element 16 will produce a mechanical hysteresis effect in that it causes a lagging or retardation of relative movement between the plunger 12 and tappet body 11 when forces acting axially upon the ends of the tappets are subjected to changes. The magnitude of this effect may be controlled by varying the clearance between the inner peripheral surface of the packing element 16 and the cylindrical portion of plunger 12 which the packing element surrounds. This mechanical hysteresis effect of the packing element 16 will quiet the operation of the tappet and will substantially obviate any possibility of the tappet bouncing or chattering with reference to the operating cam therefor.

Reference may now be had to Fig. 4 which illustrates a tappet of the construction described relative to Fig. 1, interposed between a valve 33 of an internal combustion engine and an operating cam 34 fixed to cam shaft 35. The operation of this arrangement will be clear from the above description of the construction shown in Fig. 1.

Referring to Fig. 5, a construction very similar to that disclosed in Fig. 1 is illustrated. In this construction the only modification is in the plunger 12' and relates to the manner in which the lower end of the packing spring 18 is connected to the plunger. In the construction shown in Fig. 5 an element 36 is press fitted upon the reduced end 37 of plunger 12' in order to retain the lower end of packing spring 18 connected to the plunger 12' instead of clipped in a groove in the lower end of the

plunger in the manner illustrated in Fig. 1. This construction, like that shown in Fig. 1, provides a yieldable packing element 16 of ductile material adapted to be maintained in sealing contact with the wall of the bore of the tappet body 11 by the high pressures in the hydraulic compression chamber 31 for substantially sealing the plunger 12' with respect to the tappet body 11. Such high pressures also cause the packing element 16 to be forced into and maintained in sealing engagement with the washer 15 and the valve member 14 to effect a seal with the flange 26 of plunger 12'. The coined or grooved surface of valve member 14 and the upper surface of the washer 15 are also brought into contact so that the spiral groove in the lower face of valve member 14 affords means for allowing only a definite and predetermined leakage or escape of oil from the hydraulic compression chamber 31. The construction of the remaining elements and their arrangement is the same as that illustrated in Fig. 1.

Reference may now be had to Fig. 6 which illustrates a modified form of tappet construction embodying the principles of the present invention, this construction including a cylindrical tappet body 41 provided with a bore 42, which affords the shoulder 43 for supporting a separate cylinder 44 adapted to be received within the upper end of the bore 42.

The tappet body 41 is provided with an annular recess 45 and an admission port 46 and is otherwise of substantially the same construction as that disclosed in the embodiment shown in Figs. 1 and 5. The separate cylinder 44 is provided with a cylindrical bore 47 and a reduced and bored boss portion 50 in which has been press fitted a suction tube 51 and a valve retaining cage 52. A ball check valve 53 is disposed within the cage 52 for limited movement therein and is adapted to make a fine line contact with the upper end of the bore of suction tube 51, so that the upper end of the bore wall of tube 51 forms the valve seat for the return valve 53. The upper end of the cage 52 is provided with an oil passage 54. The separate cylinder 44 preferably makes a drop or sliding fit within the upper end of the bore 42 so that air may be vented from the preliminary or reserve liquid supply chamber 55 formed by that part of the bore 42 which lies below the separate cylinder 44. The tappet plunger 56 makes a loose or sliding fit within the bore 47 of separate cylinder 44. A cylindrical washer member 57 makes a similar fit within the bore 47 of separate cylinder 44 and is arranged within the latter bore immediately below the plunger 56. A packing washer 58 of the same character as the washer 16 previously described and a packing retainer washer 61 are arranged within the bore 47 below the plunger 56 and washer 57 in the order named. A coil spring 62 is interposed between the boss portion 50 of separate cylinder 44 and the packing retainer washer 61 for extending the plunger 56 outwardly with reference to the separate cylinder until the upper end of the plunger contacts one element of a valve operated gear while the closed end of the tappet body contacts another.

An axial passage 63 extends upwardly through the packing retainer washer 61, the packing washer 60 and washer 57. That portion of the bore 47 of separate cylinder above the non-returning valve 53 and below the washer elements 57, 60 and 61 constitutes the hydraulic compression chamber 64 of the tappet.

During the operation of this tappet construction, oil or other liquid under pressure is ad-

mitted through the annular recess 45 and port 46 to the preliminary or reserve supply chamber 55. The plunger spring 62 causes extension of plunger 56 until the latter contacts one valve operating part and the closed end of the tappet body 41 contacts another valve operating part. Outward movement of the plunger 56 creates a partial vacuum condition within the hydraulic compression chamber 64 causing the valve 53 to lift from its seat and liquid medium to be drawn upwardly through the suction tube 51 into the hydraulic compression chamber 64 of the tappet. When an engine valve is lifted by the tappet, the increased pressure within the hydraulic compression chamber 64 is exerted upon the inner periphery of the yieldable packing element 60 and upon the lower surface of the latter, tending to cause the material of the packing to flow outwardly and provide a seal between the packing and the bore 47 of the separate cylinder 44. The increased pressure exerted by the liquid medium within the hydraulic compression chamber causes the adjacent surfaces of washer 57 and the yieldable packing element 60 to be pressed together and the upper surface of washer 57 and the lower surface of plunger 56 likewise to be brought into intimate contact. The surfaces are pressed together by a force substantially equal to the entire load of the valve operating gear at the time of opening of the engine valve. The leak-down rate between the plunger and separate cylinder is controlled by the lower surface of the plunger 56 and the upper surface of the washer 57, one of the surfaces either being grooved as indicated at 32 in the construction shown in Fig. 1 or one or more of these surfaces being left in a sufficiently roughened condition, not polished, to provide the proper leak-down rate between the plunger and the separate cylinder. In this construction the yieldable packing element 60 is substantially confined by the washer 57, separate cylinder 44, the packing retainer washer 61 and the oil or other liquid medium within the hydraulic compression chamber 64. Thus the yieldable or ductile packing element 60 affords substantially the same mechanical hysteresis effect in producing a lagging or retardation of movement of the plunger with reference to the separate cylinder when axial forces directed against opposite ends of the tappet are varied as in the previously described constructions. The ball valve 53 is gravity and inertia actuated as well as by differential fluid pressures to cause its return to and maintenance in seated position during lift of the tappet.

55 Referring to Fig. 7, a tappet very similar in construction to that shown in Fig. 6 is illustrated. In this construction the plunger 56', corresponding to the plunger 56 of the previously described embodiment is provided with a reduced end portion 65 adapted to contact a valve stem or other valve operating part for an exhaust or intake valve of an internal combustion engine. An abutment sleeve 66 is threaded to the upper end of the separate cylinder 44', corresponding to the separate cylinder 44 of the previously described embodiment, and the abutment sleeve 66 is spaced a considerable distance from the reduced portion 65 of plunger 56'. The abutment sleeve 66 limits outward movement of the plunger with reference to a separate cylinder so that in the event that an engine valve becomes stuck in open position the plunger cannot follow the stuck valve a sufficient distance to cause breakage of the latter or of the cylinder head of the engine. The 70 remaining parts shown in Fig. 7 correspond with

like parts shown in Fig. 6 and are given the same numerals.

In all of the illustrated embodiments, the preliminary or reserve air separation chamber is vented to atmosphere either through clearance 5 between the plunger and the bore of the tappet body as in the embodiment shown in Figs. 1 to 5, or through clearance between the separate cylinder and the bore of the tappet body as in the case of the embodiment shown in Figs. 6 and 7. 10 The ductile packing elements are forced radially outwardly by flowing the material thereof in that direction in order to seal the plunger with reference to its cylinder. A mechanical hysteresis effect is afforded by all of the illustrated embodiments due to forcing the ductile and yieldable packing to flow the material thereof outwardly against the wall of its confining cylinder, the packing otherwise being substantially confined by the plunger element or elements carried thereby 20 and the oil in the hydraulic compression chamber of the tappet so as to produce a lagging or retardation in movement of the plunger with reference to the separate cylinder when axially directed forces against the end of the tappet are 25 changed. In each of the illustrated embodiments provision is made for limiting travel inwardly of the plunger so that operation of the engine valve will be had, although with some lift loss, in the event of failure of oil supply and after oil in the 30 preliminary or reserve supply chamber has been exhausted. In the embodiment shown in Figs. 1 and 5, the lower end of the plunger 12 or the element 36 abuts the closed end 23 for limiting inward movement of the plunger with reference to the tappet body. In the embodiment shown in Figs. 6 and 7 the plunger and elements carried thereby have but a limited movement inwardly with reference to the separate cylinders 44 or 44'. 40

As many changes could be made in the above construction, and many apparently widely different embodiments of this construction could be had without departing from the scope thereof, it is intended that all matter contained in the 45 above description or showing shall be interpreted as illustrative and not in a limiting sense.

What is claimed is:

1. A hydraulic valve tappet, comprising a cylindrical body, provided with a longitudinal bore, 50 said body being closed at one end and open at the other, a plunger disposed in said bore and in conjunction with said cylindrical body defining a hydraulic compression chamber, means for admitting liquid into said cylindrical body and resilient means for extending said plunger outwardly with respect to said cylindrical body, said plunger including an annular flange providing a plain surface normal to the axis of said plunger, a plain surface valve disc positioned to abut at one face thereof the plain surface of said flange to provide a check valve, the other plain surface of said valve disc being provided with a groove of small cross-section and extended length, a second plain surface disc positioned to abut the grooved surface of said valve disc to complete a small cross-section passage of relatively long length for limiting to a slight amount leakage from said hydraulic compression chamber, and a yieldable element formed of a ductile material substantially confined by said plunger, cylindrical body and hydraulic compression chamber for effecting a seal between said plunger and cylindrical body. 65

2. In a valve tappet, a cylinder having a fluid reservoir at one end, a plunger having a body 70

- portion slidably engageable with the cylinder walls, a continuous sealing ring positioned at the end of the plunger body adjacent the reservoir and movable with the plunger, said ring having a peripheral portion of ductile material engageable with the cylinder walls to resist the escape of fluid from the reservoir past the plunger, and a pressure relief member cooperating between the sealing ring and the plunger providing for a limited escape of fluid past the sealing ring.
3. In a valve tappet, a cylinder having a fluid reservoir therein, a plunger having a body portion slidably engaging the cylinder walls, a seal comprising a member of ductile metal having a circular outer edge and positioned at the end of the plunger body adjacent the reservoir with the circular edge slidably engaging the cylinder walls throughout the circumference of said edge, said member being movable with the plunger and having an opening therethrough for the passage of

fluid, and means associated between said member and said plunger providing a restricted by-pass for fluid escaping through the opening in said member.

4. In a valve tappet, a cylinder having a fluid reservoir therein, a plunger having a body slidably engageable with the cylinder walls, a seal positioned between the plunger body and reservoir and movable with the plunger, said seal comprising a plurality of independently movable juxtaposed members having circular outer edge portions, at least one of said members being formed of ductile material frictionally engaging the cylinder walls to prevent the escape of fluid from the reservoir to the space between the cylinder walls and plunger, and means providing a by-pass through the juxtaposed members to the space between the plunger body and cylinder walls.
